(57) **CLAIM**

I claim the ornamental design for a photo luminescent cover, as shown and described.

DESCRIPTION

FIG. 1 is a front view of a photo luminescent cover;

FIG. 2 is a rear view thereof;

FIG. 3 is a side view thereof (the left and right side views being the same); and,

FIG. 4 is a top and bottom view thereof (the top and bottom views being the same).

The broken lines in the drawings are for the purpose of illustrating environmental structure and form no part of the claimed design.
